COILED STOCKHOLDING FIXTURE

Harold G. Wiebe, Chicago, Ill., assignor to Western Electric Company, Incorporated, New York, N. Y., a corporation of New York

Application January 28, 1947, Serial No. 724,727

7 Claims. (Cl. 242—105)

1

This invention relates to a coiled stock holding fixture and more particularly to a fixture for securing the outer end of spirally coiled strip stock to a stock reel while cutting the tie bands from the coil.

Long lengths of metal strip material wound in tightly wrapped spiral coils and maintained in said coiled condition by a plurality of tie bands each transversely encircling a section of the overlapping strip material, when about to be used, for example, as strip stock for a punch press, may be placed on a reel support and the tie bands severed and removed therefrom to free the strip stock for use. Coiled strip stock of relatively heavy gage, of substantial width and hard quality, possesses an inherent resiliency which creates a momentary hazard when the last tie band is removed and the coil stock begins to rapidly uncoil to a more static condition. It is to overcome the hazard thus encountered that the present invention is utilized.

An object of the present invention is to provide a fixture for securing the outer end of coiled strip material to the reel supporting the coil.

In one embodiment of the invention, one end of a coil of strip stock mounted on a reel having a plurality of radiating reel arms on either side of the coil is temporarily clamped to the reel by an elongated member having a transversely disposed end thereon forming a jaw engageable with one of the reel arms on one side of the coil and the elongated member is provided with a longitudinal way and ratchet teeth for receiving a movable jaw slidably mounted thereon to engage the reel arm on the other side of the coil, the jaw being held in adjusted position by a spring pressed pawl engaging the ratchet teeth on the elongated member of the fixture. A clamping plate adjustably secured to the elongated member by a pair of thumb screws is adapted to receive the free end of the coil between it and the elongated member and to clamp it tightly against the fixture by the adjustment of the thumb nuts, whereby the outer end of the coil is thus secured in fixed relation to the reel so that the tie bands may be removed from the coil to allow it to partly uncoil to a less stressed condition.

The invention will be more fully understood from the following detailed description thereof when considered in connection with the accompanying drawings illustrating a preferred embodiment thereof in which

Fig. 1 is a face view of the coil with the tie bands attached;

Fig. 2 is a front elevational view of a reel with a coil mounted thereon and the holding fixture in place thereon;

Fig. 3 is a fragmentary sectional view taken

2

on the line 3—3 of Fig. 2 showing a portion of the reel with a coil and the holding fixture in place thereon;

Fig. 4 is a plan view of the holding fixture indicating the portion of the reel and a portion of the strip in dot and dash lines therein and indicated as taken on the lines 4—4 of Fig. 2;

Fig. 5 is an end view of the fixture illustrated in Fig. 4; and

Fig. 6 is a sectional view taken on the line 6—6 of Fig. 4 and indicating, in dot and dash lines, the end of the coil strip clamped to the fixture.

Referring now to the drawings, particularly Fig. 1, there is shown an elongated sheet metal strip tightly wound into the spiral coil and held in tightly wound condition by a plurality of metal straps or bands 11 transversely encircling the overlapped layers of the strip material and secured thereto by seals 12. The coil 10, when ready for use, is applied to the horizontal portions 15 (Figs. 2 and 3) of adjustably mounted arm units 16 of the reel 17. Removable arms 18 of the arm units 16 are removed from the reel and the coil 10 is placed in position against the stationary arms 19, after which the removable arms 18 are replaced on the reel to confine the coil laterally between the arms 18 and 19. The arm units 16 are mounted for radial adjustment on radially disposed guide rods 20, which pass through apertures in bosses 21 on the arms 19 and by sleeves 23 rotatable on the rods 20 and exteriorly threaded to engage threads in a boss 24 on the arm 19. The threaded screws 23 are connected together through bevel gears of a suitable control mechanism by means of which the sleeves 23 may be rotated and the reel arm units 16 may be radially adjusted. With the coil 10 mounted on the reel, the tie band 11 holding the end 25 of the coil may be severed and removed to permit the end of the coil to be clamped to a holding fixture 26 and secured relative to the reel, after which the remaining tie bands 11 and 12 may be severed and removed.

The holding fixture 26 comprises an L-shaped plate 27 having an elongated leg 28 and a transversely disposed hook-shaped end 29, which forms a stationary jaw of the holding fixture. On opposite faces of the leg 28, longitudinal grooves 30—30 are provided forming a T-shaped portion 31 for slidably engaging in a T-shaped slot 32 of a block 33 adjustably mounted on the leg 28. The block 33 is recessed at 35 to form an adjustable jaw slidable on the member 27 and is held in adjusted position by a pawl 36 engageable with the ratchet teeth 37 formed on the T-shaped portion of the leg 28. Mounted for reciprocation in a recess 38 in the block 33, the pawl 36 is pressed into engagement with the teeth 37 by a spring 39 and may be moved from the teeth by

engaging a knob 40 secured to the rod 41 formed integral with the pawl 36. Thus it will be seen that the fixture may be clamped to the arms 18 and 19, which are spaced apart from each other various distances according to the width of the strip material in the coil 10.

For securing the end 25 of the coil of strip material to the fixture, a clamping plate 45 is provided and is adjustably mounted on the underneath side of the member 28 by a pair of threaded members 46 rotatably mounted in apertures in the member 28 and threadedly engaging apertures in the plate 45. The threaded members 46-46 are provided with knurled handles 47, by means of which the threaded members may be turned to move the clamping plate 45 toward or away from the member 27.

In using the holding fixture, the free end 25 of the coil is inserted between the member 27 and the clamping plate 45 and the member 27 is placed relative to the reel so that the hooked stationary jaw 29 thereon engages the guide rod 20 of the reel underneath the boss 21 of the arm 19, and the adjustable jaw 30 is moved toward the stationary jaw into engagement with the removable arm 18, as indicated in Fig. 4. The locking pawl 36 will lock the movable jaw in position on the fixture and the thumb screws 47 may then be rotated to move the clamping plate 45 to clamp the end 25 of the coil tightly against the fixture 27. Thus the fixture in the position just described serves to anchor the outer end 25 of the coil of material to a pair of arms 18 and 19 of the reel and prevent the movement thereof when the remaining tie bands 11 are removed therefrom and the uncoiling of the reel takes place. With the outer end 25 of the coiled strip fixed relative to the reel, the partial uncoiling of the strip to a static condition occurs by a movement of the inner end of the coil relative to the fixed outer end and thus involves no hazard.

What is claimed is:

1. A fixture for holding the end of a coil of strip material on a reel comprising a member, a pair of jaws carried by the member and engageable in gripping relation with said reel, one of said jaws being movable on said member relative to said other jaw, means for holding said movable jaw in adjusted position, and a clamp mounted on said member for clamping the end of said strip material to said member.

2. A fixture for holding the end of a coil of strip material in a fixed position on a reel comprising an elongated member having a fixed jaw projecting therefrom, a movable jaw slidably mounted on said elongated member, said jaws being operable to engage the reel and clamp the elongated member thereto, means for releasably holding said movable jaw in clamping position on said elongated member, and means including a clamping plate for clamping the end of said coil to said elongated member.

3. A fixture for holding the end of a coil of strip material on a reel comprising an elongated member having a fixed jaw extending laterally therefrom, a movable jaw slidably on said elongated member, a ratchet formed on said elongated member, a spring-pressed pawl carried by said movable jaw and engageable with said ratchet to hold said movable jaw in adjusted position on said member whereby the jaws may be held in clamping engagement with said reel to secure said member thereto, and a clamp on said elongated member for clamping the end of said coil to said elongated member.

4. A fixture for holding the end of a coil of strip material in a fixed position on a reel comprising an elongated member having a fixed jaw projecting transversely therefrom, a movable jaw slidably mounted on said elongated member, ratchet teeth formed on said elongated member, a spring-pressed pawl carried by said movable jaw and engageable with said ratchet teeth to hold said movable jaw in adjusted position on said member whereby said jaws may be held in clamping engagement with said reel to secure said member thereto, a clamping plate for cooperation with said member to clamp the end of said strip of material to said elongated member, and a pair of actuating members carried by said elongated member for actuating said clamping plate.

5. A fixture for holding the end of a coil of strip material in a fixed position on a spider type reel comprising an elongated member having a jaw projecting transversely therefrom, a movable jaw slidably mounted on said elongated member, ratchet teeth formed on said elongated member, a spring-pressed pawl movably carried by said movable jaw and engageable with said ratchet teeth to hold said movable jaw in adjusted position on said member, whereby said jaws may be held in clamping engagement with arms of said reel to secure said member thereto in a selected position longitudinally of said arms, a clamping plate for cooperation with said member to clamp the end of said strip of material to said elongated member, and a pair of thumb screws cooperating with said clamping plate and said elongated member for actuating said clamping plate.

6. A fixture for use in mounting coils of stock on a feed wheel associated with a processing apparatus comprising a substantially L-shaped plate having a way formed thereon, a clamping member mounted to slide in said way, a spring-pressed pawl mounted on the clamping member, a ratchet formed on the L-shaped member for cooperation with said pawl whereby the L-shaped member and its cooperating clamp may be clamped to a reel, a second clamping plate for cooperation with said L-shaped member to clamp the end of a strip of stock to said L-shaped member, and a pair of threaded actuators mounted in said L-shaped member for actuating said second clamping plate.

7. A removable fixture applicable to a reel for holding the end of a coil of strip material on said reel comprising a pair of members, adjustable means connecting said members operable to move one of said members relative to the other to clamp the end portion of the coil of strip material therebetween, and adjustable means carried by one of said members operable to clamp said members to said reel.
